(57) **CLAIM**

The ornamental design for a grape container, as shown and described.

DESCRIPTION

FIG. 1 is a top perspective exploded view of a grape container showing my new design;

FIG. 2 is a side exploded view thereof;

FIG. 3 is a side exploded view of the opposite side of FIG. 2 thereof;

FIG. 4 is a front exploded view thereof;

FIG. 5 is a rear exploded view thereof;

FIG. 6 is a top exploded view thereof;

FIG. 7 is a bottom exploded view thereof; and,

FIG. 8 is a perspective view thereof.

The broken lines are for illustrative purposes only and form no part of the claimed design.
